DRINKING CUP

Lydia Ann Higginson, 764 Paxton Ave.,
Salt Lake City, Utah 84104

Filed June 12, 1972, Ser. No. 261,672

Term of patent 14 years

Int. Cl. D7—01

U.S. Cl. D7—9

FIG. 1

FIG. 3

FIG. 2

FIG. 4

FIG. 1 is a top plan view of a drinking cup embodying my design;

FIG. 2 is a front elevational view thereof;

FIG. 3 is a top front perspective view thereof; and

FIG. 4 is a rear elevational view thereof.

I claim:

The ornamental design for a drinking cup, substantially as shown and described.
